UNITED STATES PATENT OFFICE.

LORA E. POOLE, OF ANDERSON, INDIANA, ASSIGNOR TO ANDERSON BUTTON ATTACHING MACHINE COMPANY, OF ANDERSON, INDIANA, A CORPORATION.

BUTTON-ATTACHING MACHINE.

1,215,987.

Specification of Letters Patent. Patented Feb. 13, 1917.

Application filed November 26, 1915. Serial No. 63,587.

To all whom it may concern:

Be it known that I, LORA E. POOLE, a citizen of the United States, and a resident of Anderson, county of Marion, and State of Indiana, have invented a certain new and useful Button-Attaching Machine; and I do hereby declare that the following is a full, clear, and exact description thereof, reference being had to the accompanying drawings, in which like letters refer to like parts.

The object of this invention is to provide means on a button attaching machine to attach buttons on shoes by means of a wire staple, whereby the position of the button when attached to the shoe or other article may be accurately determined by the operator before the button is attached. This device is especially adapted to be used on button attaching machines where the button is affixed on the shoe or other article by means of a wire staple. It has heretofore been difficult to determine in what position to place the article to receive the button exactly where desired. Heretofore it has been necessary for the operator to determine as nearly as possible by his eye where the button will be attached, and this is usually very difficult because of the fact that the button itself is quite a distance from the attaching place and the operation is so quick that there is always danger of the button being misplaced. By means of this invention the point of attaching the button may not only be determined, but it may also be seen just how the button will look in that position on the shoe or other article, thereby doing away with the necessity of gaging by the eye, and thereby making the operation merely mechanical.

This is accomplished by a button-like indicating ball which extends upward from the mechanism to the same relative position to the shoe or other article that the button will take, but which will be withdrawn out of the way before the button is attached.

The full nature of the invention will be understood from the accompanying drawings and the following description and claims:

In the drawings, Figure 1 is a vertical cross-section through the button attaching machine showing the indicating means in position. Fig. 2 is the same as Fig. 1, a part thereof being removed, showing the indicat-

ing means in lowered position. Fig. 3 is a front elevation showing the indicating means in position.

In the drawings, there is a button attaching machine having a hollow pedestal 10, a table portion 11, disks 12, a framework 13, a rod 14 pivoted to the disk 12 at 15 which is adapted to be operated by a pedal, not shown. Said disk operates about the point 16 and has projections 17 and 18. 65

Secured to the framework of said machine there is a hopper 20 adapted to be filled with buttons and having a feeding plate 21 extending through the bottom thereof for picking up buttons in the slot 22 for elevating 70 them in position to be fed into the button race 23. On the lower end of said plate there is a plate spring 24 adapted to be engaged by the projection 25 on the disk 12, whereby said feeding plate may be mechanically 75 lifted by the mechanism of the machine, said plate being secured to a rod 26 extending through the table 11, said rod having a spring 27 surrounding it above the table and a spring 28 below the table. There is 80 a hood 29 extending over the slot in the feeding plate and a hood 30 over the race 23 to prevent the buttons from bouncing off when being fed onto said race. The buttons are permitted to slide down said race to a button gate 31 which holds the button, as shown in Fig. 1, in readiness to be gripped by a feed finger 32. Said feed finger is pivoted to an arm 38 secured to the mechanism at 33. Said gate is pivoted at 34 and has two finger 85 members 35, one of which is adapted to engage a pin 36 on said finger so as to elevate it to a position over the button where, by means of the spring 37, not shown, the finger drops down on top of a button as 90 shown in Fig. 2, the pin 36 passing through an opening between the fingers in the upper portion of said gate. The button is then carried downward by said feed finger forcing the gate upward against a spring 37 100 which returns them into position in time to engage the following button and hold it until the said finger returns. Said finger is operated by the pedal acting through the rod 15 on the disk 12 which turns about a 105 quarter of a revolution and operates the arm 38 to which said finger is pivoted.

On the under side of the button race there is a cut-off ram 39 which is longitudinally 110 slidable in the framework of said machine

and having a slot therein in which a staple driver 40 is adapted to slide. The roller pins 17 on said disk are adapted to be engaged by two projections on said staple driver so that the movement of the disk will force the staple driver down toward the staple forming anvil 41. The same movement forces the cut-off ram toward said anvil by means of the roller pin 18 on said 10 disk engaging a cam lever 42 pivoted at 43, which in turn engages a spring member 44, which is secured to the under side of said cut-off ram, whereby the cut-off ram and staple driver are yieldingly operated.

15 Extending upwardly at right angles and in line with the button race there is a staple-forming block 45. Said block is in such position that the wire which is fed into the machine for forming the staples will extend 20 past the upper side thereof in a position to be cut and formed into a staple by means of the cut-off ram passing said block, cutting the wire thereon and forming it into a staple to be driven against the anvil and 25 clenched by the staple driver. The staple forming blocks extends downwardly into the frame of the machine 13 and has a coil spring 46 surrounding it under a head on the upper end of said block, adapted to 30 force said block upwardly into its engaging position, where it is held while the cut-off ram passes it and cuts off the wire, which it forces around said block so as to form a 35 staple. There is a shoulder on said cut-off ram which engages a shoulder on said staple-forming block and forces it downwardly against the spring 46 so as to allow the button, staple and staple driver to ride over it.

40 On said staple-forming block there is secured an arm 47 which extends outwardly and upwardly from said cut-off block and has on the upper end thereof an indicating ball 48. Said indicating means is so arranged 45 that the indicating ball will be just in front of the anvil, leaving only space enough to insert the article to which the button is to be attached, and rests in the position thereon which will be taken by the 50 button when attached. It is desirous to make the indicating ball appear as a button would when attached, so that it may be seen just how the button will appear in that position, and so that the operator may easily 55 determine where the button should be attached. When the machine is operated, the cut-off ram will engage the shoulder on the staple-forming block, forcing it downwardly out of the way of the staple driver 60 and button, which will at the same time carry the indicating means or ball downwardly with it out of the way of the button

so that it may be attached at the same point as said ball indicated.

The invention claimed is:

1. A button attaching machine including a button attaching means, a staple forming block adapted to be operated by said button attaching means, and means removable by said staple forming block for indicating where the button will be attached. 65

2. A button attaching machine including button attaching means, a staple forming block operated by said button attaching means, an arm secured to said block, and an indicating ball on the end of said arm for indicating where the button will be attached. 75

3. A button attaching machine including button attaching means, a staple forming block adapted to be operated by said button attaching means, an arm secured to said block, a staple anvil, and an indicating ball secured on said arm adjacent to said anvil 80 for indicating where the button will be attached. 85

4. A button attaching machine including a framework, a button race, an operating member, a cut-off ram slideable in said frame, a staple driver, means on said operating member for operating said ram, a staple forming block, means on said ram for forcing said block downwardly, and means operated by said block for indicating where the 90 button will be attached. 95

5. A button attaching machine including a framework, a button race, an operating member, a cut-off ram slideable in said frame, a staple driver, means on said operating member for operating said ram, a staple 100 forming block, means on said ram for forcing said block downwardly, an arm secured to said block, and an indicating means on said arm for showing the position of the button when attached. 105

6. A button attaching machine including a framework, a button race, an operating member, a cut-off ram slideable in said frame, a staple driver, means on said operating member for operating said ram, a staple 110 forming block, means on said ram for forcing said block downwardly, an anvil for clenching the staple, and an indicating means secured to said staple forming block in a position relative to said anvil for indicating where the button will be attached by the staple. 115

In witness whereof, I have hereunto affixed my signature in the presence of the witnesses herein named.

LORA E. POOLE.
